UNITED STATES PATENT OFFICE.

CLARENCE E. BEACH, OF BINGHAMTON, NEW YORK, ASSIGNOR TO GEORGE O. KNAPP,
OF NEW YORK, N. Y.

AUXILIARY ALARM SYSTEM.

1,093,679.

Specification of Letters Patent. Patented Apr. 21, 1914.

Application filed June 30, 1913. Serial No. 776,603.

To all whom it may concern:

Be it known that I, CLARENCE E. BEACH, of Binghamton, in the county of Broome and State of New York; have invented certain new and useful Improvements in Auxiliary Alarm Systems, of which the following is a specification.

My invention relates to auxiliary alarm circuits and particularly to an improved annunciator system to be used in connection with such circuits.

An auxiliary alarm circuit usually extends from a main line fire alarm box to a building or premises from which the operation of the fire alarm box is to be controlled in addition to the direct control in the ordinary manner. Such auxiliary circuits are provided with switch mechanisms suitably scattered about the building or premises to be protected, actuation of any one of said switch mechanisms causing response of the auxiliary circuit to effect starting of the fire alarm box. It is very desirable to be able to ascertain at which switch mechanism the auxiliary circuit was controlled to cause sending of a fire alarm signal. For example, the fire department answering the call would immediately be directed to the origin of the fire if indication could be given at the entrance of the building or premises of what auxiliary station was pulled.

In the co-pending application of Clarence E. Beach and Herman W. Doughty, Serial No. 689,587, filed April 9, 1912, there is shown an auxiliary controlling circuit which is in the nature of a normally closed short-circuit about the non-interference electro-magnet which controls the running of the box, and the annunciator mechanism shown receives current flow from the auxiliary controlling circuit or from a local source of current. There are other auxiliary systems in which pulling of a box is controlled by an auxiliary electro-magnet provided in addition to the non-interference electro-magnet of the box, the auxiliary controlling circuit extending from the auxiliary electro-magnet to the various auxiliary stations. Such a system is disclosed in Patent 1,016,401, issued February 6, 1912, to Frederick W. Cole.

The general object of my invention is to provide an improved annunciator system which can be effectively utilized in connection with auxiliary controlling circuit

whether such circuits be normally open, or normally closed, or normally in some other electrical condition.

Another important object is to provide annunciator mechanism whose annunciator devices are adapted to be included in the main alarm circuit to receive energizing current flow therefrom.

Another object is to provide switch mechanism sets, each adapted upon actuation to change the electrical condition of the auxiliary controlling circuit so that starting of the box and operation of the main alarm circuit can follow, and at the same time to cause connection in the main alarm circuit of the annunciator device associated with the actuated switch set.

In the accompanying set of drawings, I have diagrammatically illustrated various arrangements embodying the features of my invention, and Figure 1 shows an arrangement in which the auxiliary controlling circuit is in the form of a normally closed short-circuit about the non-interference electro-magnet of the fire alarm box; Fig. 2 shows an arrangement in which the auxiliary controlling circuit is in the form of a normally open circuit including a source of current and the auxiliary electro-mechanism for electro-mechanically controlling the starting of the fire alarm box; and Fig. 3 shows an arrangement similar to that in Fig. 1, except that the auxiliary controlling circuit is controlled electro-mechanically by the annunciator devices.

Referring to Fig. 1, I have diagrammatically illustrated various parts of the fire alarm box from which the auxiliary system extends. The non-interference electro-magnet 10 has the armature structure 11 which cooperates with detent lever 12 for controlling the pallet 13 of the signaling train 14, which train controls the operation of the signal wheel 15. When the armature is retracted, the detent lever stops the train and when the armature is attracted, the detent lever is disengaged from the pallet and the train and signal wheel can operate. The signal wheel in rotating will effect alternate opening and closure of the circuit controlling springs 16 and 17. As shown, shunt contacts 18 and 19 are also provided, which, before the box is pulled, are engaged by a shunt lever 20 and which are connected by conductors 21 and 22 with the main

55

net terminals. A pull lever 23 is provided and arranged so that on pulling of the box the shunt lever will be moved away from the shunt contacts 18 and 19 to open the shunt circuit 21 and 22. However, the auxiliary controlling circuit A is normally closed and will prevent energization of the electro-magnet even though the main shunt circuit 21, 22 is opened.

In practice, when the auxiliary control of the box is desired, the shunt lever 20 will be held away from the shunt circuit terminals 18 and 19, so that starting of the box will be entirely under control of the auxiliary controlling circuit, and when this auxiliary circuit is closed, the box cannot be started, but as soon as this circuit is opened at any point the electro-magnet will be free to be energized to attract its armature to cause release of the signaling train. The main alarm circuit M extends from a central exchange where it includes signal receiving mechanism R and a source of current S, and at the various signaling boxes this circuit includes the non-interference electro-magnet and the signal controlling contacts. Each box becomes active to send the signal as soon as the controlling electro-magnet has been released by the auxiliary controlling circuit and the train started.

At each of the various stations *a*, *b*, *c*, throughout a building or premises from which the fire alarm box is to be controlled, switch mechanism is provided, each switch mechanism comprising two separately insulated switch levers *e* and *f*, preferably connected for simultaneous operation, and cooperating with contacts *g* and *h*, respectively. The various switch arms *f* control the auxiliary controlling circuit A and normally engage their contacts to close this circuit. The various switch arms *e* are normally in engagement with their contacts *g* and serially included in the annunciator circuit T, which is in the form of a loop from the main alarm circuit M. Each switch arm *e* is bridged by a circuit including an annunciator unit *u*. As shown, the bridge annunciator circuit for the station *a* includes conductors *i* and *j*; the bridge circuit for station *b* includes conductors *j* and *k*; and the bridge circuit for station *c* includes conductors *k* and *l*.

Tracing out the operation of the system, suppose that at the signal box the shunt lever 20 has been raised to open the electro-magnet shunt circuit 21, 22 so that the box is set for auxiliary control; the various auxiliary switch mechanisms will be normally closed and the box electro-magnet will be deenergized and the annunciator devices for all the auxiliary stations will be short-circuited. If, now, an alarm is to be sent from one of the auxiliary stations, for example, station *a*, the switch mechanism at

this station is actuated and the switch arms *e* and *f* are disconnected from their contacts *g* and *h*, respectively. The auxiliary controlling circuit is thus opened to remove the short-circuit from the box electro-magnet, and at the same time the short-circuit is removed from the annunciator mechanism *u* for the station *a*. If the box signaling contacts 16 and 17 are normally closed, there will be current flow from the main source, through the electro-magnet and the signaling contacts 16 and 17 at the released box, then to the station at which the auxiliary switch has been opened and through the annunciator device for that station, and then through the signal receiving mechanism at the central station back to the battery, operating both the signal box and the annunciator device.

The annunciator mechanism may be of any well-known construction, as, for example, that in which, upon energization of an electro-magnet, a target or other indicating device is released by an armature to assume an indicating position, and after once being released, such indicating member will remain in indicating position until re-set.

When the fire department arrives, it will ascertain from the annunciator mechanism that the alarm was sent from the auxiliary station *a* and it will thus be accurately directed to the origin of the fire. After the box has thus been controlled from the auxiliary station and has sent in its signal, the various mechanisms can be re-set for subsequent alarm purposes. After the auxiliary station switch has been restored, the actuated unit at the annunciator mechanism can be re-set and the various mechanisms at the signal box can again be so arranged that the box will again be under control of the auxiliary controlling circuit. It is understood, of course, that in the drawings only part of the box mechanism is illustrated, and that the box may contain suitable non-interference mechanisms, mechanisms for stopping the box after it has properly sent its signal, etc., all this being well understood in the art.

In Fig. 2, I have shown my improved annunciator system applied to auxiliary mechanism such as shown in the Cole patent referred to. I have shown only the non-interference electro-magnet 10, the signal wheel 15, and the signal contacts 16 and 17 of the box mechanism, and the auxiliary electro-magnet E, the other parts of the box and the control thereof by the auxiliary electro-magnet being clearly shown in the patent referred to, the operation being such that when the auxiliary electro-magnet is suitably energized, its armature structure will release auxiliary actuating mechanism which will then operate to cause starting of the box

signaling train. In applying my annunciator system, the annunciator mechanism *u* and the main annunciator circuits are arranged the same as in Fig. 1, the annunciator mechanism being controlled by the switch arms *e*. The auxiliary controlling circuit *A* includes the auxiliary magnet *E* and a local source of current *L*, and I have shown switch arms *f* which are normally away from their contacts *h* and in engagement with contacts *h'*, the switch arms *f* being normally serially included in the limb *m* of the auxiliary controlling circuit, while the contacts *h* are all connected with the other limb *n* of the auxiliary circuit, so that when any switch arm *f* is moved into engagement with its contact *h*, the auxiliary controlling circuit will be adjusted to cause electro-magnet *E* to become effectively energized. At each station *a*, *b*, *c*, etc., the switch arms *e* and *f*, are preferably connected together for simultaneous operation. To describe the operation, suppose that an alarm is to be sent from one of the auxiliary stations, say station *a*. The switch arms at this station are actuated to move switch arm *e* from its contact *g* and to move switch arm *f* into engagement with its contact *h*. The auxiliary controlling circuit is then closed and the annunciator device *u* for station *a* is included in the annunciator circuit and the main alarm circuit. The signal box will be pulled as a result of operation of the electro-magnet *E* and will send in its signals. If the signaling contacts 16 and 17 are normally closed as indicated, the annunciator device for station *a* will indicate immediately upon actuation of the switch mechanism at station *a*. After the signal has been completed the actuated auxiliary station may be re-set to normal position to re-open the auxiliary controlling circuit and to short-circuit the annunciator mechanism, and the annunciator mechanism and the box may be re-set.

In Fig. 3 the arrangement shown is similar to that shown in Fig. 1, except that instead of providing manual switch members for the auxiliary controlling circuit, such circuit is electro-mechanically controlled by the annunciator devices. The annunciator mechanism electro-magnets, the annunciator short-circuits, and the main alarm circuit are arranged exactly as in Fig. 1. The indicating members of the annunciator devices coöperate with the armatures *p* of these devices to automatically control the auxiliary circuit, and as shown the indicating devices are normally held by their respective armatures and together with the armatures are normally included serially in the auxiliary circuit. To illustrate the operation, suppose that the switch arm *e* at auxiliary station *a* is moved away from its contact *g*, the short circuit about the annunciator device *u* for station *a* is opened and this device is ener-

gized and its armature is attracted to release the associated indicating device, and the auxiliary controlling circuit is opened and the box electro-magnet 10 is free to receive current flow and to effect starting of the box 70 signaling train. In each of the annunciator systems of Figs. 1, 2 and 3, provision can be made to cause each annunciator mechanism winding to be short-circuited immediately after first actuation of the device, and such arrangement is shown in Fig. 3 where a contact *r* is provided for a contact spring *t*, carried by each indicating member but insulated therefrom, these contacts being so connected that after any annunciator device winding has been primarily included in circuit to attract its armature and the indicating member is released to open the auxiliary controlling circuit, this contact spring will engage its contact and the main alarm circuit will flow through the conductor *i*, conductor *s*, and contact *r*, through the contact spring *t* attached to the released indicating member *o*, the conductor *j*, the switches *b* and *c*, and through the signaling contacts and electro-magnet at the box, the winding of the actuated annunciator device being thus shunted out of the alarm circuit. After an alarm has been sent, the auxiliary switch mechanism, the corresponding annunciator devices, 90 and the box mechanism may be re-set to be subsequently controlled by the auxiliary controlling circuit.

I do not, of course, desire to be limited to the precise arrangement and operation herein disclosed, as changes and modifications are possible, which would still come within the scope of my invention, and

I therefore claim the following:

1. In a fire alarm system, the combination 105 of a main alarm circuit including a source of current and a translating device, a fire alarm box having signaling contacts adapted for serial inclusion in said circuit, a signaling train for controlling said contacts, 110 an electro-magnet for controlling the starting of said train, a controlling circuit for said electro-magnet extending from the box to a plurality of auxiliary stations, an annunciator circuit in the form of a loop extending from the main circuit through the various stations, an annunciator device for each station, switch mechanism at each station normally closing the loop circuit and short-circuiting the annunciator devices and 115 normally adjusting the auxiliary circuit to prevent operation of the electro-magnet at the box, actuation of the switch mechanism at any station causing inclusion in the main alarm circuit of the annunciator device associated with the said station and causing adjustment of the auxiliary circuit to allow operation of the electro-magnet to cause starting of the fire alarm box.
2. In a fire alarm signaling system, the 130

- combination of a main alarm circuit, fire alarm signaling mechanism serially included in said main circuit, an electro-magnet for controlling the starting of said fire alarm 5 signaling mechanism, a controlling circuit extending from said electro-magnet to a plurality of auxiliary stations, an indicator circuit extending from the main alarm circuit to said auxiliary stations, an indicator 10 device for each station associated with said indicator circuit, and switch mechanism at each station for controlling said auxiliary circuit and indicator circuit.
3. In a signaling system, a signaling circuit including a source of current, a translating device and signaling mechanism, an auxiliary controlling circuit for said signaling mechanism, a plurality of switches in said auxiliary controlling circuit, a loop circuit included serially in circuit with said signaling mechanism, a plurality of switches in said loop circuit each associated with one of the switches in the auxiliary controlling circuit, and an annunciator device bridged 20 about each of said loop circuit switches to be normally shunted thereby, actuation of any set of associated switches causing opening of the auxiliary controlling circuit to release the signaling mechanism and causing 25 inclusion in the loop circuit of the associated annunciator device, whereby indication is given by the actuated annunciator device of the point at which the auxiliary circuit is opened.
- 35 4. In a signaling system, the combination of a main signaling circuit including a source of current, a translating device and signaling mechanism, an auxiliary controlling circuit extending from said signaling 40 mechanism as a shunt path around said mechanism to normally cause said mechanism to be unaffected by the current flow from said source, a plurality of switches in said auxiliary circuit for controlling the 45 continuity thereof, an annunciator circuit looped serially in the main circuit with said signaling mechanism, a plurality of switches in said annunciator circuit, each of said switches being associated with one of the 50 switches in said auxiliary circuit to form a switch set, an electrically controlled annunciator device associated with each of the annunciator circuit switches to be normally shunted thereby, actuation of any switch set 55 causing opening of the auxiliary controlling circuit to release the signaling mechanism and at the same time causing inclusion in the annunciator circuit of the associated annunciator device.
- 60 5. In a signaling system, the combination of a main circuit including a source of current, a translating device, and signaling mechanism, an auxiliary controlling circuit for said signaling mechanism extending 65 therefrom as a normally closed short-circuit

path around said mechanism to prevent effective operation of said signaling mechanism, an annunciator circuit paralleling said auxiliary controlling circuit and extending as a loop from the main circuit and serially including the signaling mechanism, electrically controlled annunciator devices, and a plurality of switch mechanisms normally closing both said auxiliary controlling circuit and said annunciator circuit and each adapted, when actuated, to simultaneously open the auxiliary circuit and to operatively include one of the said annunciator devices in said annunciator circuit.

6. In a signaling system, the combination 80 of a main circuit including a source of current, a translating device, and signaling mechanism, an auxiliary circuit for said mechanism extending therefrom as a normal shunt circuit about the signaling mechanism, a normally closed annunciator circuit in the form of a loop from the main line serially including said signaling mechanism, a plurality of switches in said annunciator circuit, an electro-magnetic annunciator device connected in bridge to each of said switches to be included in the annunciator circuit upon opening of the associated switch, and a switch electro-magnetically controlled 85 by each annunciator device, such electro-magnetic switches being normally serially included in said auxiliary controlling circuit whereby actuation of any annunciator circuit switch will cause inclusion in said circuit of the associated annunciator device 90 and thereby actuation of the corresponding switch in the auxiliary circuit to open said auxiliary circuit to allow the signaling mechanism to become operative.

7. In a signaling system, the combination 105 of a main circuit including a source of current, a translating device, and signaling mechanism, an auxiliary controlling circuit for said mechanism extending therefrom as a normally closed shunt circuit about the 110 signaling mechanism, a normally closed annunciator circuit in the form of a loop from the main line serially including said signaling mechanism, a plurality of switches in said annunciator circuit, an electro-magnetic 115 annunciator device connected in bridge to each of said switches to be included in the annunciator circuit upon opening of the associated switch, and a switch electro-magnetically controlled by each annunciator device, such electro-magnetic switches being normally serially included in said auxiliary controlling circuit whereby actuation of any annunciator switch will cause inclusion in said circuit of the associated annunciator device 120 and thereby actuation of the corresponding switch in the auxiliary circuit to open said auxiliary circuit to allow the signaling mechanism to become operative, and means controlled by each annunciator device for 125 130

causing short-circuiting of said annunciator device immediately after inclusion thereof in the annunciator circuit.

8. In a fire alarm signaling system, the combination of a main alarm circuit including a source of current and a translating device, a fire alarm box having signaling contacts adapted for serial inclusion in said circuit, a signaling train for opening and closing said contacts and an electro-magnet for controlling the starting of said signaling train, an auxiliary controlling circuit connected as a shunt to said electro-magnet to render it inoperative and extending from said main circuit through a plurality of auxiliary stations, an indicating annunciator circuit extending serially in the form of a loop from said main circuit and paralleling said auxiliary circuit through said auxiliary stations, an electrically controlled annunciator device for each auxiliary station normally shunted so as to be deenergized, switch mechanism at each station normally closing the auxiliary circuit and, associated therewith, switch mechanism normally short-circuiting the corresponding annunciator device, actuation of any set of associated switch mechanisms causing opening of the auxiliary controlling circuit to release the signaling train and causing inclusion in the annunciator loop circuit of the associated indicating device, whereby indication is given as to the point at which the auxiliary circuit is opened.

9. The combination of a main circuit including a source of current and a translating device, a signaling train controlled by an electro-magnet, an auxiliary shunt circuit for said electro-magnet, an annunciator circuit extending as a loop from said main circuit and containing a plurality of normally shunted indicating devices, and means at a plurality of auxiliary stations whereby the shunt may be removed from the associated indicating device to render it operative and whereby the shunt for the controlling electro-magnet may be opened to secure the operation of the signaling train.

10. In a fire alarm system, the combination of a main alarm circuit, a fire alarm box connected therewith, an auxiliary local controlling circuit in closed shunt to the controlling magnet of said box, circuit controllers in said auxiliary circuit, and annunciations corresponding thereto and adapted for operative connection with the main alarm circuit and dependent for operation upon that of the respective circuit controllers which brings into operation the signal mechanism of the fire alarm box.

11. In a signaling system, the combination of a main circuit including a source of current, a translating device, signaling mechanism, said mechanism having a normally deenergized electromagnet for controlling the

starting thereof, a circuit for controlling the energization of said electromagnet, a plurality of switch mechanisms for controlling said circuit, an annunciator circuit extending from the main circuit, a plurality of switch mechanisms associated with said first named switch mechanisms and each controlling shut paths about parts of said annunciator circuit, and an electromagnetic indicating device included in each shunt circuit energized by the operation of the associated switch mechanism.

12. In a signaling system, the combination of a main circuit including a source of current, a translating device, signaling mechanism, said mechanism having an electromagnet for controlling the starting thereof, a circuit normally preventing the energization of said magnet, switches in said circuit embodying means for energizing said magnet, an annunciator circuit extending from the main circuit and associated with said switches, said annunciator circuit having a plurality of electromagnetic indicating devices and controlling switches therefor.

13. In a signaling system, the combination of a main circuit including a source of current, a translating device, signaling mechanism, said mechanism having an electromagnet for controlling the starting thereof, a circuit normally so adjusted as to prevent energization of said electromagnet, switches in said circuit for so adjusting said circuit as to permit energization of said electromagnet, and an annunciator circuit extending from the main circuit and comprising a plurality of electromagnetic indicating devices and controlling switches therefor associated with the electromagnet controlling switches.

14. In a signaling system, the combination of a main circuit including a source of current, a translating device, and a plurality of signaling mechanisms, each mechanism having a normally deenergized electromagnet for controlling the starting thereof, a circuit for controlling the energization of said electromagnet, a plurality of switches for controlling said circuit, and an annunciator circuit extending from the main circuit and comprising a plurality of electromagnetic indicating devices and controlling switches therefor associated with the electromagnet controlling switches.

15. In a signaling system, the combination of a main circuit including a source of current, a translating device, and a plurality of signaling mechanisms, each mechanism having a normally deenergized electromagnet for controlling the starting thereof, a circuit for controlling the energization of said electromagnet, circuit controllers in said circuit, and annunciations corresponding thereto, operatively connected with the main circuit.

16. In a signaling system, the combination of a main circuit including a source of current, a translating device, and a plurality of signaling mechanisms, each mechanism having a normally deenergized electromagnet for controlling the starting thereof, a circuit for controlling the energization of said electromagnet, circuit controllers in said circuit, and annunciators corresponding thereto and adapted to be operated by current from the main alarm circuit, each of said circuit

controllers being adapted in its operation to establish connections that operate the signaling mechanism and also its corresponding annunciator.

15

In witness whereof, I hereunto subscribe my name, this 26th day of June, A. D., 1913.
